UNITED STATES PATENT OFFICE.

JAMES PERRY FISHER, OF CEREDO, WEST VIRGINIA.

PIPE WRENCH.

Application filed March 22, 1926, Serial No. 96,574, and in Canada April 5, 1924.

My invention relates to improvements in pipe wrenches, and the object thereof is to provide a simple and inexpensive device which may be successfully used for removing broken pipe ends from valves, couplings, and the like, two relatively adjustable lugs being provided for reception in the pipe end and one of said lugs being rotatably and eccentrically mounted to cause it to tightly bind against the pipe when the wrench is turned.

With the foregoing in view, the invention resides in the novel subject-matter herein-after described and claimed the description being supplemented by the accompanying drawing.

Fig. 1 is a partial side elevation of the wrench showing the manner of using the same;

Fig. 2 is a vertical sectional view partly in elevation;

Fig. 3 is a fragmentary edge view; and

Fig. 4 is a detail sectional view as indicated by line 4—4 of Fig. 2.

In the drawing above briefly described, the numeral 1 designates an operating handle having a head 2 at one end whose upper portion 3 constitutes a jaw member. This jaw member preferably carries a slidably mounted jaw face 4 provided with teeth to engage the exterior of a pipe or the like. Another jaw member 5 co-acts with the jaw member 3 and is preferably provided with teeth 6 opposed to the jaw face 4. I have shown a threaded shank 7 on the jaw member 5, passing through a guide 8 in the head 2 and provided with an adjusting nut 9 so that the distance between the two jaw members may be adjusted as required.

The parts so far described may be of the construction shown or any other desired construction to provide suitable relatively adjustable carrying members for a pair of projecting lugs 10 and 11 which are adapted for reception in a pipe end. In Fig. 1, such a pipe end has been illustrated at 12, threaded into a valve or coupling 13 and broken off even with the end of the latter, making it impossible to use an ordinary pipe wrench for its removal. By inserting the lugs 10 and 11 and suitably adjusting the carrying members thereof, however, the pipe end may be easily removed from the valve or the like.

In the preferred form of construction, the lug 10 is stationary and is provided with a sharp pipe-engaging edge 14. In the pres-

ent showing, the inner end of this lug is provided with a squared projection 15 secured rigidly in any suitable manner, in a squared socket 16, formed in the jaw member 3.

The lug 11 is formed with a transversely curved longitudinally tapered, peripheral, pipe-engaging surface 17 preferably having suitable teeth, and means are provided for rotatably and eccentrically mounting this lug to permit it to tightly bind against the pipe end when the wrench is turned. In the present disclosure, the inner end of the lug 11 is provided with an integral cylindrical head 18 which is eccentrically located with respect to the curved surface 17, said head being rotatably received in a cylindrical socket 19 formed in the jaw member 5. To retain the head 18 in the socket 19, said head is preferably formed with a peripheral groove 20 into which one or more retaining screws or the like 21 extend from the jaw member 5.

With the lug 11 turned to dispose it as shown in Figs. 1, 2, and 3, the two lugs 11 and 10 are inserted into the pipe end to be removed, and the jaw members 3 and 5 are relatively adjusted to bring said lugs into contact with the pipe. Then as the handle of the wrench is turned, the lug 11 turns upon its eccentric rotary mounting and thus both lugs are tightly engaged with the pipe and the latter may be easily removed.

As excellent results may be obtained from the details disclosed, they may be followed if desired, but within the scope of the invention as claimed, numerous minor changes may be made.

I claim:

A wrench comprising a pair of connected relatively adjustable lug-carrying members, a fixed and a movable lug projecting from said members for insertion in a pipe, the movable lug being formed with a transversely curved, longitudinally tapered, peripheral pipe-engaging surface, said movable lug being provided at its inner end with an integral cylindrical head eccentrically located with respect to the curved surface, said head being adapted to be rotatably mounted in a cylindrical socket of its carrying member, and means to hold said head against longitudinal movement and yet permit it to rotate.

In testimony whereof I have hereunto affixed my signature.

JAMES PERRY FISHER.
